UNITED STATES PATENT OFFICE.

CAROLINE B. McKINLEY, OF WASHINGTON, DISTRICT OF COLUMBIA.

DESIGN FOR A COSTUME.

58,447.

Specification for Design.

Patented July 19, 1921.

Application filed December 23, 1920. Serial No. 432,879. Term of patent 7 years.

To all whom it may concern:

Be it known that I, CAROLINE B. McKINLEY, a citizen of the United States of America, residing at Washington, in the District of Columbia, have invented a new, original, and ornamental Design for a Costume, of which the following is a specification, reference being had to the accompanying drawing, forming part thereof.

In the drawing:

Fig. 2 is a rear elevation of the same.

I claim:

The ornamental design for a costume, as shown.

CAROLINE B. McKINLEY. [L. S.]
